[57] CLAIM

The ornamental design for an anchor pad and release layer, as shown and described.

DESCRIPTION

FIG. 1 is a front-right side perspective view of an anchor pad and a release layer in accordance with a preferred embodiment of the present invention;

FIG. 2 is a top plan view of the anchor pad with release layer of FIG. 1;

FIG. 3 is a bottom plan view of the anchor pad with release layer of FIG. 1;

FIG. 4 is a front side elevational view of the anchor pad with release layer of FIG. 1;

FIG. 5 is a rear side elevational view of the anchor pad with release layer of FIG. 1;

FIG. 6 is a right elevational view of the anchor pad with release layer of FIG. 1;

FIG. 7 is a left elevational view of the anchor pad with release layer of FIG. 1;

FIG. 8 is a front-right side perspective view of the anchor pad of FIG. 1;

FIG. 9 is a top plan view of the anchor pad of FIG. 8;

FIG. 10 is a bottom plan view of the anchor pad of FIG. 8;

FIG. 11 is a front side elevational view of the anchor pad of FIG. 8;

FIG. 12 is a rear side elevational view of the anchor pad of FIG. 8;

FIG. 13 is a right elevational view of the anchor pad of FIG. 8;

FIG. 14 is a left elevational view of the anchor pad of FIG. 8;

FIG. 15 is a front-right side perspective view of an anchor pad and a release layer in accordance with another preferred embodiment of the present invention;

FIG. 16 is a top perspective view of the anchor pad with release layer of FIG. 15;

FIG. 17 is a bottom plan view of the anchor pad with release layer of FIG. 15;

FIG. 18 is a front side elevational view of the anchor pad with release layer of FIG. 15;

FIG. 19 is a rear side elevational view of the anchor pad with release layer of FIG. 15;

FIG. 20 is a right elevational view of the anchor pad with release layer of FIG. 15;

FIG. 21 is a left elevational view of the anchor pad with release layer of FIG. 15;

FIG. 22 is a front-right side perspective view of the anchor pad of FIG. 15;

FIG. 23 is a top plan view of the anchor pad of FIG. 22;

FIG. 24 is a bottom plan view of the anchor pad of FIG. 22;

FIG. 25 is a front side elevational view of the anchor pad of FIG. 22;

FIG. 26 is a rear side elevational view of the anchor pad of FIG. 22;

FIG. 27 is a right elevational view of the anchor pad of FIG. 22; and,

FIG. 28 is a left elevational view of the anchor pad of FIG. 22.
